Thomas A. Phillips
ATTORNEY

UNITED STATES PATENT OFFICE.

JOHN MACKENZIE, OF SYRACUSE, NEW YORK.

SEAL-LOCK.

1,326,761.

Specification of Letters Patent.

Patented Dec. 30, 1919.

Application filed April 11, 1919. Serial No. 289,325.

To all whom it may concern:

Be it known that I, JOHN MACKENZIE, citizen of the United States, residing at Syracuse, in the county of Onondaga and 5 State of New York, have invented certain new and useful Improvements in Seal-Locks, of which the following is a specification.

My invention relates to improvements in 10 seal locks, that is to say particularly to the type or character of lock or hasp used upon sliding car doors, and the improvements are in the general nature of the seal lock forming the subject matter of patent granted to 15 me October 8, 1912, No. 1,040,713.

One object of my invention is to improve generally upon the construction of the lock covered by the patent referred to and make its construction more reliable and efficient 20 in operation and entirely practical in all important respects.

Another object of my invention is the provision of a seal lock of the character stated which will be composed of few parts 25 to insure simplicity, durability and cheapness of production and which will prove highly desirable for use upon freight cars.

Another object of my invention is the provision of a seal or hasp lock which will 30 retain the parts of which it is composed in proper relative position and which will secure the seal and co-acting bolt in proper relation and provide the necessary safe guards required in a lock of this character.

With these objects in view the invention broadly stated consists of a rigid member or casing having a chamber and a receiving staple, a locking bolt slidable in the casing and staple and formed with a notch, a seal 35 disposed in the casing and spaced away from the locking bolt, and a spring swingingly supported in the casing and having one portion to engage the notch of the locking bolt and the other portion bearing 40 against the rear face of the seal to secure said seal and bolt.

The invention further consists of a seal or hasp lock of the character described embodying novel features of construction and 45 combination of parts for service, substantially as shown, described and particularly defined by the claims.

In order that the detailed construction and the operation of my lock may be more 50 completely understood and its many advantages and features of merit be appreciated,

I have shown in the accompanying drawings a practical construction for carrying my invention into effect, but I would have it understood that I do not confine myself 60 to the construction illustrated, but reserve the right to make any changes which fall within the scope of the claims.

In the said drawings:

Figure 1 is a front view showing the invention securing a hasp of the usual kind 65 in locked position.

Fig. 2 is a side view taken on the line 2—2 of Fig. 1.

Fig. 3 is a sectional view taken on the 70 line 3—3 of Fig. 2, and

Fig. 4 is a longitudinal section on the line 4—4 of Fig. 1.

Referring by numerals to the drawings in which the same numerals of reference are 75 used to denote the same parts in all the views:

The reference numeral 5 indicates the fixed part of the car to which the lock base 6, is secured by the fastenings 7, the car 80 door of the sliding type is indicated at 8, and is provided with a hasp 9, having the usual slot 10, adapted to receive the staple 11, which is carried by the lower flat part 12, of the lock, this staple has an opening 85 13, through which the bolt 14, reciprocates.

The lock consists of the chambered casting 15, through which the bolt 14 reciprocates. In the top of this chamber is a slot 17, which the pan shaped seal 18 fits and 90 slides in. On the upper end of the bolt 14, is the protecting cap 16, which rests upon the upper wall of the chamber 15, and covers said slot 17, thereby preventing entrance of rain, snow, or other extraneous matter. 95 When in position the lower edge of the seal rests on the bottom wall of the chamber 15, and the upper part is confined behind the depending part 19, from the upper wall of the chamber, the lower part of the seal being held in place by the spring 20, which 100 is hung on the pin 21, and has two wings or oppositely diverged portions, the outer of which bears against the seal 18, and the inner of which engages the notch 22, of the 105 bolt 14.

The chamber 15 is open in the front so that when the seal has been removed, the spring 20, may be readily swung through the opening 23, and the bolt 14 be released. 110 The pin 24 is placed in the bolt 14, to prevent its removal. The lower end of the

bolt is formed with a slot 25, for use with a seal such as indicated at 26, in Fig. 2.

In the operation of my device the bolt 14 is withdrawn and the seal 18, is slid into position through the opening 17. The hasp is placed over the staple 11, and the bolt with its protecting cap is pushed down through the opening 18, until the spring 20, engages the notch 22, thus locking or sealing the car door. The seal can be easily broken with a nail or any pointed implement.

The advantages of a lock constructed according to my invention will be readily understood and appreciated by persons conversant with such structures and it will be apparent that the parts may be instantly secured in locked position and the seal be disposed to indicate whether the lock is safe or has been tampered with; also that the construction of the suspended spring causes one part to lock the bolt and the other to secure the seal; also that the lock is composed of few parts of strong and durable construction to prevent the lock from being damaged by the usual hard usage to which such locks are subjected; also that the lock may be applied cheaply to cars in use or at the time of their manufacture; and that generally in every important respect the lock will prove reliable, efficient and practical.

I claim:

1. A lock of the character described, consisting of a base formed with a casing having an open portion, bolt receiving openings, and a hasp receiving staple, a hasp having an opening to fit over said staple, a locking bolt mounted in the openings of the casing and having a notch, a seal disposed in the open portion of the casing and visible from the exterior, and a pendant locking device, mounted to swing through the open portion of the casing and consisting of a two part spring member compressible between the bolt and seal, one part of which engages the seal and the other part engages the notch of the bolt.

2. A lock of the character described, consisting of an anchoring base, a casing mounted thereon, a hasp receiving staple

adjacent said casing, a seal fitted in the front of the casing, a locking bolt mounted in the casing and spaced away from said seal, and a spring locking member compressible by the bolt between the seal and bolt and simultaneously engaging said seal and bolt to lock the same in relative positions.

3. A lock of the character described, consisting of an attaching base, a casing mounted on said base and having an open front and bolt receiving openings, a staple in line with said openings, a locking bolt fitting said openings and co-acting with said staple, and provided with a notch, a protecting cap and means to limit its movement in said casing, a seal movable in the casing and disposed in the open front thereof, and a spring locking member swingingly mounted and compressible by the bolt between the bolt and seal and having a part engaging the notch of the bolt and a part bearing against the rear wall of the seal.

4. A lock of the character described, consisting of a hasp having an opening, a staple to engage said opening, a base carrying said staple, a chambered casing adjacent said staple, a bolt slideable in said casing and engaging the staple to lock the hasp, a seal in said casing spaced away from the bolt, a pin between the bolt and seal, and a two part compressible spring locking member hung upon said pin, and having one free end bearing against said seal and the other free end having locking engagement with the bolt to secure the seal and bolt in relative positions.

5. A lock of the character described, consisting of a casing, a seal fitting in said casing at the front thereof, a locking bolt reciprocable in said casing in rear of said seal, and a spring locking device compressible between the bolt and seal and having a pair of spring arms, one having locking engagement with the bolt and the other bearing against the inner face of the seal.

In testimony whereof I affix my signature.

JOHN MACKENZIE.
